(57) **CLAIM**

We claim the ornamental design for a writing instrument cap, as shown and described.

DESCRIPTION

FIG. 1 is an upper perspective view showing our new design for a writing instrument cap.

FIG. 2 is a lower perspective view showing the design of FIG. 1.

FIG. 3 is a first side view showing the design of FIG. 1.

FIG. 4 is a second side view showing the design of FIG. 1.

FIG. 5 is a third side view showing the design of FIG. 1.

FIG. 6 is a fourth side view showing the design of FIG. 1.

FIG. 7 is a top view showing the design of FIG. 1.

FIG. 8 is a bottom view showing the design of FIG. 1.

FIG. 9 is a first perspective view showing the design of FIG. 1 in combination with a writing instrument having the cap positioned over the writing end of the writing instrument.

FIG. 10 is a second perspective view showing the design of FIG. 9; and,

FIG. 11 is a third perspective view showing the design of FIG. 9.

The broken lines showing a pen in FIGS. 9-11 are for the purpose of showing environment and form no part of the claimed design. All other broken lines illustrate portions of the writing instrument cap that form no part of the claimed design.

1 Claim, 8 Drawing Sheets
